WILHELM BERTIL BRONANDER, OF MONTCLAIR, NEW JERSEY, ASSIGNOR TO INTERNATIONAL CIGAR MACHINERY COMPANY, A CORPORATION OF NEW JERSEY

VOLUMETRIC MEASURING DEVICE FOR CIGAR MACHINES

Application filed May 25, 1929. Serial No. 365,959.

This invention relates to filler feeds for cigar machines of the type in which the filler is intermittently fed into a charge forming space, and in particular to measuring devices of such feeds by which operation of the feed is interrupted after a quantity of tobacco sufficient for one charge has been fed into the space. Hitherto the amplitude of the feeding action has been controlled by the length of the charge in the charge forming space. Hence when the layer of cigar filler on the feed belt, which is laid thereon by hand and is subject to considerable variation, was of less than normal depth, the charge, while of proper length and density in the direction of feeding, would be of less than normal volume because of less than normal depth. It is, of course, apparent that in order to produce uniform cigars, each bunch charge must contain the same volume of tobacco at the same density, in short, the same quantity of tobacco.

The principal object of the present invention therefore is to insure this uniformity by controlling the feeding in accordance with both the length and depth of the charge. To this end it is an object of the invention to provide means for varying the amplitude of the feeding action so that a layer of filler tobacco in the charge forming space that is of greater than normal depth, will be cut off shorter than when the layer is of less than normal depth, in order to produce uniform bunch charges.

Generally speaking, this is accomplished by providing in addition to the usual means, including an element in the path of the advancing tobacco, for controlling the feeding action in accordance with the length and longitudinal density of the tobacco in the charge forming space, a weighted depth measurer which rests upon the top of the tobacco layer in the charge forming space. Suitable mechanism is provided by which this depth measurer and the means controlled by the longitudinal density of the layer both coact to control or vary the amplitude of the feeding action.

With these and other objects not specifically mentioned in view, the invention con-

sists in certain constructions and combinations which will be hereinafter fully described and then specifically set forth in the accompanying claims.

In the accompanying drawings which form a part of this specification and in which like characters of reference indicate the same or like parts:

Fig. 1 is a side elevation, partly in cross section, of an automatic filler feed mechanism to which the present invention has been applied. The improved mechanism is shown in heavy lines and the old feed mechanism to which it has been applied is shown in lighter lines.

Fig. 2 is an end elevation of the mechanism shown in Fig. 1.

Figs. 3 and 4 are diagrammatic side elevations of a part of the mechanism shown in Fig. 1, showing the relative positions of the several parts at different stages of operation.

In carrying the invention into effect, there is provided mechanism for intermittently feeding a continuous mass or layer of cigar filler to the charge severing position, a device for controlling the longitudinal density of the mass at said position, a device for measuring the depth of the mass at said position, and means controlled by the action of said device for varying the amplitude of the feeding action in accordance with variations in the coaction of said devices to produce uniform charges despite variations in the depth of the cigar filler layer. In the best constructions, said mechanism includes a feed belt and actuating means therefor controlled by said means. Preferably the means controlled by the coaction of said devices operates to increase the feeding action when the depth of the mass is sub-normal and to decrease it when the depth of the mass is super-normal. Preferably also, a weight actuated measurer is provided, together with means actuated by said measurer, for varying the amplitude of the feeding action in accordance with variations in the action of said measurer.

The above mentioned parts and means may be widely varied in construction within

the scope of the claims, for the particular structure selected to illustrate the invention is but one of many possible embodiments of the same. The invention, therefore, is not to be restricted to the precise details of the structure shown and described.

Referring to Figs. 1 and 2 of the drawings, the cigar filler tobacco is carried by the feed belt 5 and star wheels 6 and 7 under suitable guides 8 into the charge forming space 9. The tobacco advances therein against the fingers 10 until the density of the accumulated mass balances the weight arm 11 rigid therewith, which is fixedly mounted on the pivot shaft 12 carrying the frame 13 to which the fingers 10 are secured. The weight arm 11 carries the fixed weight 14 and also adjustable weights 15 on a rod 16 by means of which the density of the bunch charge may be changed to suit conditions. The parts above mentioned serve to control the longitudinal density of the mass in charge severing position. After the accumulated mass has reached the desired density, the fingers 10 move with the charge until a predetermined volume of tobacco passes the plane of the severing knife herein-after described.

A device is provided for measuring the depth of the mass at this position comprising a weighted measuring shoe 17 which rests on the top of the filler charge. This measurer carries weights 18 on rods 19 and is suspended above the charge forming space 35 by means of adjustable screws 20 from star wheel bracket 21, so that when there is no filler in the charge forming space, the measuring device drops to a low position at which its shoe shaped lower portion is ready 40 to ride on the upper surface of the next incoming layer of filler tobacco. The weights 18 are made adjustable and enable the measuring device to control the density of the tobacco mass in the direction of its depth, 45 in order that said mass may be measured at a predetermined density uniform for successive charges. To guide the measuring device 17 in its vertical movement, it is movable in slideways 22 attached to the bracket 50 21. This bracket is fixed to the cigar machine frame by means of suitable slotted angle pieces 23 and 24 by which the height of the bracket may be adjusted as desired. Thus, the vertical position of the measuring device 17 is determined by the depth of the mass under it.

Means are provided by which variations in the position of the measurer 17 cause it to coact with the device for controlling the 60 longitudinal density of the charge forming mass to vary the feeding action. These means include a trip arm 25 connected to the measurer for oscillation thereby, by bell crank levers 26 and 27 mounted on a shaft 65 28 swinging in the bracket 21. The hori-

zontal bell crank lever 26 connects with the measurer 17 by a ball and socket joint. The vertical bell crank lever 27 is connected to the trip arm 25 by stud 29. This trip arm 25 is weighted at its other end and has on its lower side a lug 31, preferably provided with a roller which rests on the circumference of an annular trip segment 32 which is fixedly mounted on the shaft 12 and is thus swung thereon in response to movement of the fingers 10. The shaft 12 also serves to connect the frame 13 with the outer end of the frame 33 swinging on shaft 34 on the frame 35 of the cigar machine, of which this mechanism forms a part.

In the charge forming position (Fig. 1 and dotted line positions in Figs. 3 and 4), the trip arm 25 is held in its rest position by the segment 32 engaging with the lug 31. In its trip position, when the lug 31 passes the end of the annular surface of the segment 32, this arm 25 drops onto the crank lever 33 pivoted on stud 37 and comes to rest on the stop 38.

Thus, after the charge in the space 9 has attained proper density, the advancing mass of filler tobacco overcomes the weight of the arm 11 and pushes the measuring fingers 10 forward until the proper length has passed the severing point, after which the knife 39 descends and cuts off a charge. Meanwhile, the cam segment 32 is swung with the fingers 10 sliding under the lug 31 until the lug disengages from the segment, tripping the arm 25. The arm then falls on the lever 36 and trips the lever 40 with which the same is connected by link 41.

Lever 40 strikes the screw 42, raising the weight 43 attached to the arm 44 pivoted on stud 45 and thereby trips a bell crank on a stud 47 so that its hammer shaped end 48 disengages a pawl 49 from a ratchet 50, thereby stopping feeding action of the driving drum 51 and the feed belt 5 and also that of the star wheels 6 and 7 through mechanism more fully set forth in a copending application S. N. 301,499, filed August 23, 1928, by Victor G. Hanson.

In the operation of the device selected to illustrate the invention (Figs. 3 and 4), the belt 5 carries the filler layer F placed thereon by hand, under the star wheels 6 which compress and level the same and feed it under the guides 8 and into the charge forming space 9. The filler layer is then raised by the fingers 10 until the mass has attained a longitudinal density sufficient to raise the weight arm 11. Likewise, this layer having pushed under the lower surface of the weighted measurer, is compressed to a predetermined vertical density and raises said measurer more or less in accordance with the depth of the layer. In Fig. 3, this measurer is shown in two positions, full lines indicating the position when raised by a

charge of supernormal depth and dotted lines indicating the same with respect to a charge of sub-normal depth. The higher position of the measurer due to a charge of greater than normal depth, causes the bell crank levers 26 and 27 to move the trip lever 25 longitudinally so that the lug resting on the annular surface of the segment 32 is nearer the tripping end of said segment. Hence, less movement of the fingers 10 longitudinally of the tobacco mass will be required to swing the segment 32 to a position at which the arm 25 will be tripped than when the layer under the measurer is of less than normal thickness. Thus, layers of greater than normal thickness will be cut off shorter than layers of less than normal thickness and a uniform volume and quantity of tobacco provided in each charge, despite variations in the depth of the layer. When the lug 31 passes the end of the annular surface of segment 32, the arm 25 being tripped, strikes bell crank lever 36, thereby tripping the lever 46 and stopping the feed as already described. When the feed is stopped, the charge is severed, the fingers 10 are pulled down by the rod 52 cam operated by means on the cigar machine not shown, into the full line position shown in Fig. 4, at which position the transfer rake 53 removes the severed charge. The rod 52 then ascends, bringing the fingers 10 back to initial position, and by engagement of the segment 32 on the lug 31 lifts the trip lever 25 to its original position ready for measuring the next charge.

A filler feeding and charge forming mechanism has thus been provided in which successive charges will not merely be of uniform size and density lengthwise of the filler layer, but which will contain uniform amounts of tobacco, taking into consideration the size and density of the charges both lengthwise and depthwise of the tobacco layer, eliminating objectionable lack of uniformity in successive bunches made therefrom.

What is claimed is:

1. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said devices.
2. The combination with mechanism for intermittently feeding a continuous mass of cigar filler to charge severing position, of a device for controlling the longitudinal density of the mass at said position, a device for measuring the depth of the mass at said

position, and means controlled by the coaction of said devices for varying the amplitude of the feeding action in accordance with variations in the coaction of said devices, said mechanism including a feed belt 70 and actuating means therefor controlled by said means.

3. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said devices, said means operating to increase the feeding action when the depth of the mass is subnormal and to decrease it when the depth of the mass is supernormal.

4. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said devices, said means including a link and bell cranks connecting said link with said devices and with said mechanism.

5. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said devices, said depth measuring device including 100 a weight-actuated measurer reciprocating in 105 a direction transverse to the path of the mass.

6. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said devices, said depth measuring device including 115 a weight-actuated measurer and means connecting it with said means at varying times.

7. The combination with mechanism for intermittently feeding a continuous mass of cigar filler to charge severing position, of a device for controlling the longitudinal den- 120 125 130

sity of the mass at said position, a device for measuring the depth of the mass at said position, and means controlled by the coaction of said devices for varying the amplitude of the feeding action in accordance with variations in the coaction of said devices, said depth measuring device including a weight-actuated measurer, an arm oscillated thereby, a shaft rocked by said arm, a second arm oscillated by said shaft, a lever moved by said second arm, and means controlling engagement at varying times of said lever with said means.

8. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said devices, said depth measuring device including a trip lever and a trip segment coacting therewith to control the time of engagement of said device with said means.

9. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said devices, said density controlling device including a weight-actuated measurer, an arm supporting said measurer at its free end, and means for oscillating said arm to move said measurer in and out of the path of the mass.

10. The combination with mechanism for intermittently feeding a continuous mass of cigar filler to charge severing position, of a device for controlling the longitudinal density of the mass at said position, a device for measuring the depth of the mass at said position, and means controlled by the coaction of said devices for varying the amplitude of the feeding action in accordance with variations in the coaction of said device, said measuring device including means for controlling the density of the mass in the direction of its depth.

11. The combination with mechanism for intermittently feeding a continuous mass of cigar filler to charge severing position, of a device for measuring the depth of the mass at said position, and means actuated by said device for varying the amplitude of the feeding action in accordance with variations in the action of said device.

12. The combination with mechanism for

intermittently feeding a continuous mass of cigar filler to charge severing position, of a device for measuring the depth of the mass at said position, and means actuated by said device for varying the amplitude of the feeding action in accordance with variations in the action of said device, said device including a weight-actuated measurer reciprocating in a direction transverse to the path of the mass.

13. The combination with mechanism for intermittently feeding a continuous mass of cigar filler to charge severing position, of a device for measuring the depth of the mass at said position, and means actuated by said device for varying the amplitude of the feeding action in accordance with variations in the action of said device, said device including a weight-actuated measurer and means connecting it with said means at varying times.

14. The combination with mechanism for intermittently feeding a continuous mass of cigar filler to charge severing position, of a device for measuring the depth of the mass at said position, and means actuated by said device for varying the amplitude of the feeding action in accordance with variations in the action of said device, said device including a weight-actuated measurer, an arm oscillated thereby, a shaft rocked by said arm, a second arm oscillated by said shaft, a lever moved by said second arm, and means controlling engagement at varying times of said lever with said means.

15. The combination with mechanism for intermittently feeding a continuous mass of cigar filler to charge severing position, of a device for measuring the depth of the mass at said position, and means actuated by said device for varying the amplitude of the feeding action in accordance with variations in the action of said device, said device including a trip lever and a coacting trip segment controlling the time of engagement of said device with said means.

16. The combination with mechanism for intermittently feeding a continuous mass of cigar filler to charge severing position, of a device for measuring the depth of the mass at said position, and means actuated by said device for varying the amplitude of the feeding action in accordance with variations in the action of said device, said device including a measurer arranged to exert a predetermined pressure on the mass in the direction of its depth whereby the depth thereof will be measured at a predetermined density.

In testimony whereof, I have signed my name to this specification.

WILHELM BERTIL BRONANDER.
